Patented Nov. 18, 1969

216,025

SINGLE STUDY CARRELL UNIT

John L. Gianfagna, 102 Crestwood Circle,
Marietta, Ohio 45750

Continuation-in-part of design application Ser. No.
9,035, Oct. 18, 1967. This application July 17,
1968, Ser. No. 12,807

Term of patent 14 years

Int. Cl. D6—01

U.S. Cl. D33—11

FIG. 1.

FIG. 2

FIG. 3.

FIG. 4.

FIG. 5.

FIG. 6.

FIG. 7.

FIG. 8.

FIG. 1 is a front perspective view of a single study carrell unit showing my new design;

FIG. 2 is a top view thereof;

FIG. 3 is a rear elevational view thereof;

FIG. 4 is an elevational view taken from a side thereof;

FIG. 5 is a front perspective view of a second embodiment of my new design for a single study carrell unit;

FIG. 6 is a side view of the FIG. 5 embodiment;

FIG. 7 is a front view of the FIG. 5 embodiment; and

FIG. 8 is a top view of the FIG. 5 embodiment.

This application is a continuation-in-part of design application No. 9,035, filed Oct. 18, 1967 and now abandoned.

I claim:

The ornamental design for a single study carrell unit, substantially as shown.
